US00D830442S

(12) **United States Design Patent** (10) **Patent No.:** **US D830,442 S**
(45) **Date of Patent:** **** Oct. 9, 2018**

(54) **MONITORING CAMERA**

(71) Applicant: **AXIS AB**, Lund (SE)

(72) Inventors: **Andres Vigren**, Hollyviken (SE); **Louise Wiberg**, Malmo (SE); **Daniel Ahman**, Lomma (SE); **Mathias Walter**, Arlov (SE); **Mikael Adervall**, Klagshamn (SE); **Morten Bergstrom**, Bjarred (SE); **Rasmus Anderberg**, Malmo (SE); **Mats-Ake Ekbladh**, Bjarred (SE)

(73) Assignee: **AXIS AB**, Lund (SE)

(**) Term: **15 Years**

(21) Appl. No.: **29/567,208**

(22) Filed: **Jun. 7, 2016**

(30) **Foreign Application Priority Data**

(57) **CLAIM**

The ornamental design for a monitoring camera, as shown and described.

DESCRIPTION

FIG. 1 is a perspective view of a monitoring camera showing our new design;

FIG. 2 is a front elevational view thereof;

FIG. 3 is a left side view thereof;

FIG. 4 is a right side view thereof;

FIG. 5 is a bottom view thereof;

FIG. 6 is a top plan view thereof; and,

FIG. 7 is a rear elevational view thereof.

(Continued)

The broken lines shown in the drawings depict portions of the monitoring camera that form no part of the claimed design.

1 Claim, 5 Drawing Sheets
